UNITED STATES PATENT OFFICE.

ALBERT KRAUTH, OF HAMILTON, OHIO; FRITZ G. DIESBACH ADMINISTRATOR OF
ALBERT KRAUTH, DECEASED.

MANIFOLDING-MACHINE.

1,294,119.

Specification of Letters Patent. Patented Feb. 11, 1919.

Application filed June 3, 1915. Serial No. 31,830.

To all whom it may concern:

Be it known that I, ALBERT KRAUTH, a citizen of the United States, and residing at Hamilton, in the county of Butler and State 5 of Ohio, have invented a new and useful Improvement in Manifolding-Machines, of which the following specification is a full disclosure.

My invention relates to manifolding machines and in particular to the devices for controlling the withdrawal of the paper.

These machines generally contain webs or strips of paper representing printed blank form, as bills of lading, or sales records sub- 15 dividing the strip into definite lengths of sheets which as used are withdrawn from the machine and severed from the strip. It has been found desirable to limit the free withdrawal to the length of the sheets so 20 that a succeeding sheet is restrained within the machine to maintain its registry with its duplicate manifold sheets, and proper position over the writing table of the machine, and otherwise facilitate the operation in the 25 use of the machine.

It is customary in the manufacture of the printed strips to perforate the same at pre-determined spacing longitudinally, usually at the head of each sheet for filing purposes.

30 The invention herein therefore has as an object to provide a manifolding machine with means appropriately located adapted in the withdrawal of the paper to engage with an alined aperture when advanced in regis- 35 try therewith, restraining and limiting a continued free withdrawal of the paper or displacement within the machine of a suc- ceeding portion of the strip until the de- vices are released for a subsequent opera- 40 tion.

Various other features and objects of the invention will be more fully disclosed by the accompanying drawing and description thereof forming a part of the specification, 45 and in such drawings like characters of reference denote corresponding parts throughout the several views of which:—

Figure 1 is a central vertical section of the forward portion of a manifolding machine or autographic register containing my invention.

Fig. 2 is an end elevation of the upper forward portion of the machine shown in Fig. 1, with parts thereof broken away and others

in section to more clearly illustrate parts 55 which would otherwise be hidden.

Fig. 3 is a detail side elevation of the mechanism for supporting and controlling the paper feed arresting devices.

Fig. 4 is a detail sectional view of a modified construction of paper feed arresting devices from that illustrated in Fig. 2.

Fig. 5 is a top plan view of the machine shown in Fig. 1 with part cut away to expose hidden parts.

Fig. 6 is a sectional view similar to Fig. 1, showing the parts in a released position.

Fig. 7 illustrates a modification of the paper feed arresting devices located toward the end of the machine.

Generically this invention is companion to that disclosed in my prior patents, Reissue No. 14,189, dated Aug. 29, 1916, for autographic register, and No. 1,212,509, for manifolding devices, in providing a member 75 yieldingly urged against a surface of the paper and in the path of longitudinally alined and spaced apertures, adapted in withdrawing the paper when in registry with an aperture to engage therewith through the 80 paper, limiting or arresting further withdrawal of the paper.

Such type of mechanism in practice has been found very efficient and the sheet delivery of an entire web length is absolutely 85 accurate as to their measured lengths correspondingly with the printed form contained on each sheet, and no adjusting of the paper is necessary after the initial threading operation. The arresting mechanism is not 90 dependent in its operation upon any determined degree of motion, corresponding to a proposed length of paper withdrawal or feed, for the paper with its apertures is instrumental in limiting or arresting its withdrawal or feed from the machine. Thus slight variations in relative sheet lengths will not disturb a proper length of withdrawal, corresponding with the full length of the sheet printed form. The strips are 100 printed and perforated approximately in one operation, thus any slight variation in the texture of the paper or its feed in printing is not detrimental to the use of the strip in the manifolding machine, nor does the 105 variation, due to contraction and expansion of the paper in the web, interfere, but the paper is only arrested in the withdrawal

from the machine after a full sheet movement irrespective of any size variation of the several successive sheets.

The machine herein illustrated comprises a type in which the paper at one end of the machine is grasped by the operator and pulled forwardly until arrested, after which it is cut from the strip across a tearing-blade, but the invention is applicable to other types of manifolding devices wherein the paper is fed by crank-operated feeding rolls or other feeding devices. It comprises the usual side frames 1, 2, secured upon a base 3, between which the supply webs of paper 4 are suitably mounted and journaled with the number of supply webs depending upon the size and use of the register. The paper strips from the web are each respectively fed over guide rollers 5 to guide the paper across a writing table 6, secured between the upper portion of the side frames 1, 2, and marginally inclosed by a margin frame, which is omitted from the drawings.

At the forward end of the margin frame, slightly above the writing-table a cross-plate 7 is provided, its ends fixed to the side frames and provides an abutment for the tension blade 8 fixed to the spring tensioned rock rod 9 journaled in the side frames, the paper passing through the channel formed by the writing-table and cross-plate 7 and locked against reactionary movement by the tension blade 8. A tearing blade 10 extends across the writing table and integral with the side arms 11 projecting downwardly and slidably guided between the respective guide-ways formed by the ribs 12, projecting from the side frames, which guide the knife in its vertical movement toward and from the writing table.

The side frames support and journal a shaft 14, one end extended beyond the side frame 1, upon which a hand lever 13 is fixed exterior of said side frame. The hand lever 13 has a forwardly projecting arm 15, pivotally connected to an angle extension projecting from the arm 11 of the tearing-blade, the pivotal connection between element 15 and arm 11 being such as to provide a slight play between the parts to accommodate for the arc of movement of the arm 15 for raising the tearing-blade 10. The opposite end of the shaft 14 is provided with an arm 15', connecting with the arm 11' of the tearing-blade, for equalizing the movement at both ends of the tearing-blade and preventing any bind in the movements of the tearing-blade.

The paper arresting mechanism at the forward end of the machine is dependingly supported from the tearing-blade and comprises a cross-plate 17 having the pins 18, 18, fixed thereto, the pins projecting upwardly each through a sleeve boss 19 as a part of the tearing-blade. The free ends of the pins are

each provided with a collar or head 20 as an abutment to limit the movement of the pins toward the writing table. A spring 21 is provided for each of the pins engaged between the cross-plate 17 and tearing blade 10, for yieldingly urging the cross-plate downwardly away from the upper surface of the tearing-blade and moving the pins 22, fixed to the cross-plate 17, through the apertures 23, 24, respectively in the cross plate 7 and writing table 6, and thereby extend across the paper feeding channel to limit the movement of the paper when the pins 22 engage with the apertures in the paper. These pins when not in registry with an aperture engage against the surface of the paper, as it is being withdrawn under a slight tension not sufficient to retard or interfere with a free withdrawal of the paper until an aligned aperture is moved into registry with a respective pin, whence the pins will be moved through the paper and thereby limit or arrest further withdrawal until the pins are released, the release of the pins being coincident with the upward movement of the tearing-blade to free the knife edge 10' from its contact with the paper, and also providing more convenient accessibility to the ends of the paper strip, so that they may be grasped by the operator for a successful paper withdrawing operation.

A spring 25 coiled around one end of the shaft 14, having one end thereof fixed to the shaft and its other end secured to the side frame 2 (see Fig. 2) is provided for rocking the shaft in a return or reverse direction, for automatically moving the parts connected to said shaft to their normal position, after the operator has released his hold or hand pressure from the handle 13. Thus, as soon as the operator releases the hand lever 13, the tearing-blade is lowered, which suspends the cross-plate 17 at an elevation to permit the detents or pins 22 to be brought upon the paper, and yieldingly sustained by the springs 21, so that the pins will snap through successive apertures in the paper when brought into registry with the pins to arrest the paper motion. The spring 25 connecting with shaft 14 exerts its force to release the arresting mechanism to an operative position but does not influence the detents or pins in their paper intercepting motion through the apertures in the paper.

In the modification shown in Fig. 4, it will be seen that the pins 22' are rigidly fixed to the writing table 6 and project slightly above the same, and the cross-plate 17 is provided with an aperture 26 adapted to concentrically engage over the pin 22' for engaging a registering aperture in the paper fed between the table 6 and cross-plate 17.

At the rear end of the machine similarly functioning arresting mechanism is pro-

vided comprising a pair of yielding blades 27, 27', fixed to the lower surface of the writing table and relatively spaced, which blade is provided with a pin 28 adapted to 5 project through an alined aperture 29 in the writing table and through respective alined apertures in the cross - plate 30 extending across the writing table and fixed to the side frames. An actuating bar 31 is slidably 10 supported upon the lower surface of the writing table having one end provided with a wedge piece 32 adapted to engage a connecting bar 33 fixed to the plates 28, 28'. The opposite end of the actuating bar 31 15 pivotally connects at 31' to an arm 34 fixed upon the rock shaft 14 for moving the actuating bar 31 simultaneously with the hand lever 13 for releasing the rear retaining pins 28, 28', with a release of the forward retaining pins 22, 22'.

The operation and construction of the rear retaining members is similar to that shown and described in my aforesaid prior application, Serial No. 10,917, filed February 27, 25 1915.

In Fig. 7 I have illustrated a modification of the rear arresting mechanism, operating similar to that illustrated in Fig. 4. In such construction I provide the cross-bar or plate 30 with a pin 35, and the blade 37 with a bowed end 36 apertured to engage over the pin 35, when the blade is released toward the cross plate after an alined aperture in the paper moves into registry with the pin 35. The 35 tension of the blade 27 is very slight so as not to interfere with the feed of the paper or multilate the same, so that the tenacity of the paper will maintain the arresting elements disengaged until an aperture follows 40 in the registry therewith.

To lock the detents or pins 22 and 28 in a non-paper intercepting position, primarily of advantage when loading the machine, I provide a rock shaft 38 extending across and 45 journaled within the side frames 1 and 2, (see Figs. 1 and 6), which shaft is manually rocked by the handle 39 fixed to the shaft and extended forward so as to be accessible. The shaft 38 has an arm 40 fixed 50 thereon at one end and exterior adjacent the side frame 1. The arm 40 engages a cam extension 42 formed integral with the arm 15 of the hand lever 13, for controlling and rocking the shaft 14. The handle 39 is 55 adapted to engage with a notch 43 formed in the flange or rib 44 projecting from the side frame 1, for locking said handle in an adjusted position. Thus when the handle is moved downward to engage with the notch 43, shaft 38 will be rocked, imparting motion to the arm 40 and arm 15 to move the tearing - blade upwardly away from the writing-table, and also operating shaft 14, moving the detent controlling mechanism 60 65 connected with said shaft.

Having described my invention, I claim:

1. In a manifolding machine, a pair of side frames, a writing table connecting said frames over which a strip of paper is drawn, the paper longitudinally having spaced 70 apertures, said table at its forward end having an aperture in alinement with the apertures of the strip of paper, a tearing blade spanning said writing table and movable toward and from the same, means for 75 moving said blade, a pin member mounted upon and movable with said tearing blade and yieldingly urged toward said writing table adapted to engage with a registering aperture in the moving paper and with an 80 aperture in the writing table to intercept the progress of the paper, and tension means for said pin member.

2. In a manifolding machine, a frame structure including a writing table over 85 which a strip of paper is drawn, the paper provided with longitudinally spaced apertures, a bar member sustained across the writing table having a spring tensioned pin dependingly mounted thereon engaging 90 with an aperture in the paper when in registry therewith, and means for raising said bar member with its pin to a position where the pin cannot engage the paper.

3. In a manifolding machine comprising 95 a suitable frame work inclosing a strip of paper having a longitudinally disposed series of alining perforations, in combination with a tearing blade situated at the front end of said framework above the strip 100 of paper and having pins yieldingly urged toward the paper and arranged to enter said perforations *seriatim*, and means for moving said blade upward for withdrawing the pins from said perforations. 105

4. In a manifolding machine comprising a suitable frame work from which strips of paper are withdrawn, the combination with a writing table over which the paper passes, of a vertically movable tearing blade located adjacent the forward end of said table, 110 depressible pins supported upon said tearing blade that engage said paper, and means moving said blade thereby raising said pins to a paper non-engaging elevation. 115

5. In a manifolding machine comprising a suitable frame work from which strips of paper are withdrawn, the combination with a writing table over which the paper passes, of a vertically movable tearing blade 120 located adjacent the forward end of said table supporting depressible pins that engage said paper, means moving said blade, vertically depressible pins located at the rear end of said table that engage said 125 paper, and means for connecting with said first-named means for moving said last-named pins.

6. In a manifolding machine comprising a suitable frame work inclosing a strip of 130

paper having a longitudinally disposed series of alining perforations, in combination with a tearing blade situated at the front end of said frame work and having 5 pins arranged to enter said perforations *seriatim*, means for moving said blade upward for withdrawing the pins from said perforations, vertically depressible pins located toward the rear end of said frame 10 work arranged to enter said perforations *seriatim*, and means connected with said first named means for withdrawing said last-named pins from said perforations.

7. In a manifolding machine comprising 15 a suitable frame work, in combination with a writing table over which a strip of paper

passes, the paper having a longitudinally disposed series of alining perforations, a tearing blade located at the forward end of said writing table, a depressible pin supporting member mounted upon said tearing blade having pins arranged to enter said perforations *seriatim*, and means for moving said tearing blade upward for withdrawing said pins from said perforations. 20 25

In witness whereof, I hereunto subscribe my name, as attested by the two subscribing witnesses.

ALBERT KRAUTH.
